UNITED STATES PATENT OFFICE

170,444

BASE FOR TABLE LAMPS

Emil Bertolozzi, Chicago, Ill.

Application April 22, 1953, Serial No. 24,625

Term of patent 7 years

(Cl. D48—20)

To all whom it may concern:

Be it known that I, Emil Bertolozzi, a citizen of the United States of America, residing at Chicago, State of Illinois, have invented a new, original, and ornamental Design for a Base for Table Lamps, of which the following is a specification, reference being had to the accompanying drawings, forming a part hereof.

Fig. 1 is a front perspective view of a base for table lamps, showing my new design; and

Fig. 2 is a rear perspective view thereof.

I claim:

The ornamental design for a base for table lamps, as shown.

EMIL BERTOLOZZI.
